H. C. Lounsbury

ATTORNEY.

UNITED STATES PATENT OFFICE.

THOMAS CLOOVAS, OF YORKVILLE, OHIO.

CIGAR AND CIGARETTE HOLDER.

1,289,666.

Specification of Letters Patent. Patented Dec. 31, 1918.

Application filed June 3, 1918. Serial No. 233,069.

To all whom it may concern:

Be it known that I, THOMAS CLOOVAS, a subject of the King of Greece, and resident of Yorkville, county of Jefferson, and State of Ohio, have invented certain new and useful Improvements in Cigar and Cigarette Holders, of which the following is a specification.

This invention relates to a holder for 10 cigars and cigarettes, and it has for its primary object to provide a device whereby a lighted cigar or cigarette may be so supported upon the hand as to leave such hand 15 free for unobstructed use in the performance of ordinary tasks.

A further object of the invention is to provide a device of the character mentioned embodying features which render it applicable to various minor uses.

20 In describing the invention in detail, reference is herein had to the accompanying drawings, in which—

Figure 1 is a side elevation of the invention, slightly enlarged;

25 Fig. 2 is an elevation of the invention, still further enlarged, viewed from a point at right angles to the viewpoint in Fig. 1;

Fig. 3 is a section taken approximately on the line 3—3, Fig. 1;

30 Fig. 4 is an enlarged upper end view;

Fig. 5 is an enlarged section on line 5—5, Fig. 1; and—

Fig. 6 is an enlarged side elevation of the pin and pin encircling spring.

35 Referring to said drawings, in which like designating characters distinguish like parts throughout the several views—

1 indicates a spring clasp of open-ring form composed of resilient sheet material 40 and adapted to be slipped over a finger to firmly seating position. Rigidly carried on the outer surface of said clasp at a point substantially midway between its ends is a threaded stud 2 upon which is mounted the 45 interiorly threaded inner end portion 3^a of a hollow tube-like member 3 which has an integral centrally apertured transverse wall or web 3^c at its inner end. Projecting outward through the aperture of said web 3^c 50 is a pin 4 having a head 4^a on its inner end and having its opposite end threaded, as shown at 4^b, said threaded end being projected outward beyond the corresponding end of the tubular body 3. A head 5 is

threaded upon said threaded end 4^b of the 5^a pin and has in its inner side a socket 6 within which is received the outer end of the tubular body 3. A coil spring 7 disposed in encircling relation to said pin has its inner end resting upon the transverse web 3^c and 60 its outer end seated against said head 5 at the bottom of the socket 6.

As is obvious, the head 5 and pin 4 are together rotatable with respect to the tubular body 3, and said spring serves to normally hold said parts projected outward in a position wherein the head 4^a of said pin frictionally engages the web 3^c, whereby chance rotation is resisted.

Rigidly mounted, as by soldering, upon 70 the outer part of the head 5 opposite the socket 6 is a resilient member or clamp 8 of expandible ring form and preferably composed of flat material. Said ring 8 is designed to receive within its embrace a cigarette or cigar and to yieldingly clamp the same, as shown. The opposite end portions of said ring are of reduced width so that they cross each other without lateral bending and form projecting wings 8^a. 80

Employed as a holder for a cigar or cigarette, the device is applied in an upright position over the back of a hand by slipping the clasp 1 over a finger of the hand. The head 5 may be rotated to dispose at any 85 desired angle the cigar or cigarette held by the ring 8, it being only necessary to depress said head against the tension of the spring 7 until the head of the pin 4 is removed from engagement with the web 3^c 90 and then to rotate said head to the desired position.

An aperture 11, preferably of triangular form, and bounded by beveled edges, may be provided at a suitable point in the clasp 95 1, as shown in Fig. 2, the same being designed to serve as an emergency point-sharpener for lead pencils. Also, there may be provided in the opposite sides of said clasp diagonally extending open slots 12, the 100 slots being oppositely inclined. Such slots are designed to receive therein the edge of the flowing end of a necktie and an underlying portion of the wearer's shirt for clamping the former to the latter when the device 105 is not otherwise employed.

Various other uses may be made of the device, but since the features adapting it

for such uses form no part of the present invention, description thereof is here omitted.

What is claimed is—

- 5 1. A holder for cigars or cigarettes, comprising a resilient finger clasp, a tube-like member carried by said clasp and having a transverse web therein, a headed pin disposed within said member and extending through said web, a head mounted on the outer end of said pin and rotatably embracing the end of said member, resilient means normally holding said pin in an outwardly thrust position in which its head frictionally engages said web, and a resilient open ring carried by said rotatable head.
- 10 2. A holder for cigars or cigarettes, comprising a resilient finger clasp, a tube-like member carried by said clasp and having a transverse web therein, a headed pin disposed within said member and extending through said web, a head mounted on the outer end of said pin and rotatably embracing the end of said member, a coil spring interposed between said head and said web, and a resilient open ring mounted on said head.
- 15 3. A holder for cigars or cigarettes, comprising a resilient finger clasp, a tube-like member carried by said clasp and having a transverse web therein, a headed pin disposed within said member and extending through said web, a head mounted on the outer end of said pin and rotatably embracing the end of said member, a coil spring interposed between said web and said member and normally holding said pin in an outwardly thrust position in which its head frictionally engages said web, and a resilient open ring carried by said rotatable head.
- 20 4. A holder for cigars or cigarettes, comprising a resilient finger clasp, a tube-like member carried by said clasp and having a transverse web therein, a headed pin disposed within said member and extending through said web, a head mounted on the outer end of said pin and rotatably embracing the end of said member, resilient means normally holding said pin in an outwardly thrust position in which its head frictionally engages said web, and a clamp carried by said rotatable head.
- 25

a transverse web therein, a headed pin disposed within said member and extending through said web, a head mounted on the outer end of said pin and rotatably embracing the end of said member, resilient means normally holding said pin in an outwardly thrust position in which its head frictionally engages said web, and a resilient open ring carried by said rotatable head.

4. A holder for cigars or cigarettes, comprising a resilient finger clasp, a tube-like member carried by said clasp and having a transverse web therein, a headed pin disposed within said member and extending through said web, a head mounted on the outer end of said pin and rotatably embracing the end of said member, resilient means normally holding said pin in an outwardly thrust position in which its head frictionally engages said web, and a clamp carried by said rotatable head.

In testimony whereof, I affix my signature in presence of two subscribing witnesses.

THOMAS CLOOVAS.
